Primary Examiner — Mary Ann Calabrese*Assistant Examiner* — Sloan Rozin(74) Attorney, Agent, or Firm — IPro, PLLC(57) CLAIM

The ornamental design for a happy birthday dinosaur banner, as shown and described.

DESCRIPTION

FIG. 1 is a front view of the design; and,

FIG. 2 is a back view thereof.

The broken line showing elements on the happy birthday dinosaur banner illustrate portions of the article and form no part of the claimed design.

1 Claim, 2 Drawing Sheets(56)
